UNITED STATES PATENT OFFICE.

GEORGE P. ROSE, JR., OF DUBUQUE, IOWA, ASSIGNOR TO THE TELEGRAPH,
OF DUBUQUE, IOWA, A CORPORATION OF IOWA.

DESK FOR HOTEL-REGISTERS.

SPECIFICATION forming part of Letters Patent No. 688,696, dated December 10, 1901.

Application filed July 5, 1901. Serial No. 67,148. (No model.)

To all whom it may concern:

Be it known that I, GEORGE P. ROSE, Jr., a citizen of the United States, residing in the city and county of Dubuque, State of Iowa, 5 have invented certain new and useful Improvements in Desks for Hotel-Registers; and I do hereby declare the following to be a full, clear, and exact description of the invention, which will enable others skilled in the art to 10 which it appertains to make and use the same.

My invention relates to various improvements in the construction and use of desks for hotel-registers, more particularly such as have glass advertising show-cases attached 15 to the desk; and one of the objects is to provide means for adjustably attaching the show-case to the desk, whereby it may be held at a given angle or turn over entirely off from the register.

20 Another object is to lock down the show-case upon one page of the register, whereby the desk may be turned up or over and the show-case held firmly on the register and also hold the register on the desk when thus turned 25 wholly or partly over.

Another object is to provide means whereby the register will also be held rigid on the desk and not subject to movement in any direction when registration is entered thereon.

30 A further object is to improve the construction of the show-case whereby it will be rendered much more rigid and less liable to breakage of the glass, as well as furnish larger and better opportunity for advertising purposes.

35 The manner of construction by which I obtain these various objects and others of less importance will be fully set out and described in the following specification when taken in connection with the accompanying drawings, 40 forming a part hereof.

Figure 1 is a perspective of my device, taken from one corner. Fig. 2 is a perspective of one corner of the desk and register thereon, together with the standard for adjustably attaching the show-case, the balance of the desk 45 cut away. Fig. 3 shows a back view of the desk and of the show-case when raised to a right angle with the desk. Fig. 4 shows a front view of the desk with the show-case 50 down and the locking device attached thereto and also the locking device engaging the pin

in dotted lines. Fig. 5 shows a portion of the rod for attaching the show-case and the pin for locking it in an opened position. Fig. 6 shows the formation of the show-case with 55 parts cut away. Fig. 7 is a cross-section through line X X of Fig. 6.

Like letters of reference denote corresponding parts in all of the drawings.

Referring to the drawings, A designates 60 the desk, which consists of a board preferably covered with cloth and surrounded on three sides with wooden strips a, provided with metallic, ornamental, and staying corner-strips b. Along the front side of the desk is 65 placed a strip B, which is somewhat wider than the width of the board A and wider than the strips a, the object of which will presently appear.

Upon the rear opposite corners of the desk 70 A are secured standards D. These standards consist of two plates d and e, united together and attached to the desk by the screw E. The plate e has one of its edges cut away on its under side sufficient to allow the cover of 75 the register G to be slid in under the part b of the plate e, whereby the register-book is firmly held from movement at its upper opposite corners. The standards D are also provided with an upright portion H, set at 80 right angles to the plates d and e. Through the upright H is an oblong hole I, and projecting at right angles from each of the said uprights is a pin K, the objects of which will presently appear.

85 The show-case L is constructed in the following manner and consists of two pieces of channel-bar-shaped metal k, shaped with rounded corners o. These two parts are united together by a metal strip p, brazed to 90 the inner side of one of the strips and fastened to the other strip by the screw q.

Constructing the show-case in two pieces and firmly uniting them together renders it as rigid as though cast of one piece of metal 95 and reduces the danger of the breakage of the glass therein to almost the minimum. Within this show-case in the upper side when the case L is resting upon the register is first placed a plate-glass M. (Shown in Figs. 6 and 7.) 100 Next to this, facing toward the glass, is the advertising-sheet N. Upon this is placed a

board O, and against the board O is a hotel-guide P, facing downward or in the opposite direction from the advertising-sheet N, and upon the under side is placed a transparent celluloid plate Q, which serves to protect the hotel-guide P. Near the opposite lower rear corners of the show-case are rigidly secured the rectangular loop R, for the purpose presently to appear.

10 For the purpose of adjustably attaching the show-case to the desk and for conveniently operating the same there is placed in the slots I of the upright portion H a bar S. (Shown in Fig. 5.) This bar S is made of metal, of rectangular shape and preferably hollow. At its ends the bar is made solid and round to form the bearings in the slot I. Between the bearings s of the body of the bar is a shoulder T, and through this shoulder passes the pin U, which projects a short distance on one side of the shoulder and is adapted to engage the pin K on the upright H and hold the show-case rigidly in an open or upright position at nearly a right angle to the plane of the desk. This bar is passed through the metal loops R, attached to the show-case, and finds its bearings in the standards H.

15 To the forward end of the show-case when it is closed down upon the register is secured a locking-plate V. (Shown more particularly in Fig. 4.) This plate is provided with hooked arms t. Into the forward edge of the desk are inserted two pins W, with which the hooks t engage and lock the show-case down upon the register, as shown in dotted lines in Fig. 4.

20 The mode of operating my device is substantially as follows: The register G is placed upon the desk A, with its upper opposite corners underneath the part b of the plate e and the lower portion of the cover of the register rigidly set against the raised portion of the strip B. In this manner it will be seen that the register will not move in any direction 25 when the party is registering or writing upon the book and can only be moved by raising it up off from the register. This holding of the register rigidly upon the desk is of great value in the practical use of this class of desks. The show-case, filled and attached as hereinbefore described, when resting upon one page of the register will be firmly locked down by the engagement of the hooks t with the pins W, and when the desk is raised up 30 for any cause the show-case will not fall back and become liable to be broken. When it is necessary to unlock the show-case and raise it for change of registers or different page of the register or to consult the hotel-guide, the 35 show-case may be pushed along on the bar

until the hooks have been disengaged from the pin W, and the show-case may be raised to the position as shown in Fig. 3. If it is desired to turn the show-case over entirely off from the register and the desk, then the 40 show-case when it has been turned to the position shown in Fig. 3 may be vertically raised with the rod S in the slots I until the pin U has become disengaged from the pin K, and then the show-case may be laid over back 45 off from the desk. This use of the show-case is of great convenience in many ways.

Having now described my invention, what I claim, and desire to secure by Letters Patent, is—

75 1. In a device of the character described, a desk, a show-case, a register thereon and means for locking the show-case and register upon the desk, consisting of a plate secured to the show-case and provided with hooks, and pins attached to the desk with which the hooks engage, as and for the purposes shown.

2. In a device of the character described, a desk, a show-case, a register thereon, means for holding the register upon the desk, consisting of plates adapted to engage the upper corners of the register and a strip projecting above the front of the desk against which the register rests, and means for locking the show-case and the register upon the desk, as 85 and for the purposes shown.

3. In a device of the character described, a desk, a show-case, a register thereon, means for holding the register upon the desk consisting of plates adapted to engage the upper 95 corners of the register and a strip projecting above the front of the desk against which the register rests, and means for locking the show-case and the register upon the desk, consisting of a plate attached to the show-case, hooks upon said plate, pins secured in the desk with which the hooks engage, all 100 combined, as and for the purposes shown.

4. In a device of the character described, a desk, a show-case adjustably attached to the 105 desk and means for holding the show-case at an angle to the desk, consisting of uprights, secured to the opposite sides of the desk, slots in said uprights, a pin projecting from said uprights, a rod loosely engaging the show-case and having its bearings in said slots and pins upon said rod adapted to engage the pins upon the uprights, all combined substantially as and for the purposes shown.

110 In testimony whereof I have signed my name in the presence of two witnesses.

GEORGE P. ROSE, JR.
